No. 774,342.

PATENTED NOV. 8, 1904.

H. D. STROUD.
BURGLAR ALARM SYSTEM.
APPLICATION FILED DEC. 22, 1902.

NO MODEL.

UNITED STATES PATENT OFFICE.

HAROLD D. STROUD, OF CHICAGO, ILLINOIS, ASSIGNOR OF ONE-HALF TO
A. MILLER BELFIELD, OF CHICAGO, ILLINOIS.

BURGLAR-ALARM SYSTEM.

SPECIFICATION forming part of Letters Patent No. 774,342, dated November 8, 1904.

Application filed December 22, 1902. Serial No. 136,274. (No model.)

To all whom it may concern:

Be it known that I, HAROLD D. STROUD, a citizen of the United States, residing at Chicago, in the county of Cook and State of Illinois, have invented a certain new and useful Improvement in Burglar-Alarm Systems, of which the following is a full, clear, concise, and exact description, reference being had to the accompanying drawings, forming a part 10 of this specification.

My invention relates to burglar-alarm systems; and its object is to provide a simple, practical, effective, and reliable system for indicating the presence of burglars in a house 15 or building. I desirably provide for the automatic indication of this fact and also for its manual or hand indication.

In the arrangement for carrying out my invention herein set forth I provide a telephone-transmitter at some suitable place—as, for example, the locality from which the alarm is to be given—and also a phonograph which is arranged to speak into the transmitter. At the central station I provide a suitable telephone receiving apparatus, whereby the speaking of the phonograph into the transmitter can be heard at the central station. The phonograph is arranged to speak certain predetermined phrases—such, for example, as, 25 “Burglar at 120 State street.” This it will repeat over and over again. At the locality from which the alarm is to be given there is arranged suitable apparatus by which the alarm can be manually or automatically given.

30 In the former case the alarm can be given by the depression of a key, which action releases the phonograph and throws the transmitter in circuit, so that at once the phonograph begins to speak into the transmitter and the latter transmits the message to the central station. I desirably provide means at the central station whereby signal will be given there to call attention of an operator as soon as the phonograph is put into operation. In the arrangement for automatically giving the alarm I conveniently provide a circuit which is normally kept in a closed condition with a battery and extend this circuit in such manner and to such places that it will become broken

or opened by the entry of the burglar into 50 the house or building. The breakage or opening of the circuit automatically releases the phonograph, which thereupon speaks into the transmitter as before, and also automatically releases the mechanism for causing a signal 55 to be displayed and repeated at the central station.

In the accompanying drawing, the figure is a view illustrating a burglar-alarm system embodying my invention, having two arrangements, one operable by hand and the other automatically.

Referring to the drawing, I have shown at A the hand-operated alarm, at B the automatically-operated alarm, and C is the central 60 station to which the alarms are transmitted.

The manually-operated alarm at A consists of a spring-actuated phonograph *a*, having a rotary fan-wheel *b*. The latter is arranged to be engaged so as to hold the phonograph 70 against action by a key *c*. I also provide a telephone-transmitter *d*, which is understood to be properly arranged to receive the message delivered by the phonograph when the same is in operation. The transmitter *d* is included in a circuit *e*, which is closed at *f* by the key *c*, the key being arranged, as will be seen, to release the fan-wheel *b* of the phonograph *a* and close the transmitter-circuit at 75 the same time when depressed. I also desirably provide a rotary cam *g*, which is understood to be connected with the phonograph *a* so as to be driven thereby, and arrange this cam so as to actuate a bell-crank *h*, included in the transmitter-circuit *e*. The repeated 80 actuations of the bell-crank *h* by the cam *g* causes the transmitter-circuit to be repeatedly broken and closed. This is done for a short period of time at the beginning of the phonograph actuation. The gearing by which 85 the cam *g* is operated is then thrown out of gear by an arm or projection *d'* in the transmitter *d* striking a pivoted lever or arm *a'*, which is connected with a gear-wheel on the shaft of the phonograph *a*. I also desirably 90 provide a switch *i* in the transmitter-circuit *e*, adapted to normally maintain said circuit closed, but arranged to open the same when 95

the phonograph has operated its full extent, as by the traveling of the cylinder to the end thereof. A convenient manner for bringing about this operation is to arrange a push *j*, 5 which will be struck by the end of the reproducer of the phonograph to swing the switch *i* and open the circuit. By this arrangement it will be seen that the depression of the key *c* will release the fan-wheel *b*, thereby allowing the phonograph to operate, and will at the same time close the transmitter-circuit *e*. The operation of the phonograph causes the message thereof to be spoken into the transmitter *d* for transmission to the central station, and the operation of the phonograph also causes the cam *g* to actuate the switch *h*, and thereby repeatedly open and close the transmitter-circuit to give a repeated signal at the central station at the beginning of the operation 15 for the purpose of attracting the attention of the central office. When the phonograph has operated to its full extent or to any predetermined extent, the switch *i* is automatically opened, thereby opening the transmitter-circuit. 20

The automatically-operable alarm apparatus at *B* consists of the same mechanism as the hand-operable arrangement at *A*, excepting as to the means for closing the transmitter-circuit and releasing the phonograph. At *B* this is done automatically instead of by hand, as at *A*. A convenient arrangement is to provide a local circuit *k*, including a local battery *l* and relays *m* and *n*. The relay *m* has an armature *o*, which is arranged to engage the fan-wheel *b* of the phonograph when attracted by the relay *m* and to release the fan-wheel, and thereby release the phonograph *a*, when released by the deenergization of the relay *m*. 30 This armature is also included in the relay-circuit and is adapted to maintain the same open when attracted by the relay *m* and to release the same when released thereby. The relay *n* has an armature *p*, which is included in the local circuit *k*, and is arranged to maintain that circuit closed when attracted by the relay *n*, but to open the circuit when such relay becomes deenergized. In this arrangement it will be seen that the local circuit *k* is 35 closed and is maintained in a closed condition so long as conditions are normal, in which arrangement the armatures *o* and *p* are attracted to their respective relays, the former holding the transmitter-circuit open and holding the phonograph against operation and the latter holding the local circuit closed. Upon the breakage of the local circuit *k*, however, the armatures *o* and *p* are released, the former releasing the phonograph and permitting it 40 to operate and simultaneously closing the transmitter-circuit and the latter opening the local circuit *k*. This armature *p* is so mounted that it falls down when released, so that a subsequent closure of the circuit *k* at a broken point will not restore it. The operation of

the phonograph, transmitter, and signaling mechanism when the phonograph is released and the transmitter-circuit closed is the same as in the hand-operated mechanism at *A*.

At the central station *C*, I provide a receiver *q* in a local induction-circuit *r* therefor. I also provide a switch-hook *s* for the receiver *q* and include the same in the line-circuit *t*, which is connected with the transmitter-circuits *e e* and inductively related to the local receiver-circuit *r*. The hook *s* is arranged to hold the line-circuit *t* normally open and to close the same when the receiver *q* is lifted from the hook *s*. By this arrangement the messages transmitted from the alarm-stations can be listened to by an attendant at the central station by taking the receiver *q* from its hook. I also desirably provide a transmitter *u*, by which communication with an alarm-station can be given, if desired. At 80 the central station I also arrange a branch circuit *v* of the line-circuit *t* and include therein a local battery *w* and a relay *x*. The armature *y* of the relay *x* is included in a derived circuit *z*, which also includes an alarm-bell 1 90 or other suitable alarm device. The branch circuit *v* is desirably provided with impedance-coils 2 2. By such arrangement the opening and closing of a transmitter-circuit *e* by the cam *g* and switch *h* at an alarm-station causes the relay *x* to be energized and de-energized according as the transmitter-circuit is closed or opened. When the relay *x* is energized, its armature *y* will be attracted, thereby closing the local circuit *z* and ringing 100 the alarm-bell 1. The repeated opening and closing of a transmitter-circuit therefore causes the bell 1 to alternately ring and remain silent. The impedance-coils 2 2 prevent the voice-currents passing through the 105 battery. At the central station I also desirably provide a spring-jack 3 and plug 4 and connect the same with the line-circuit *t*. This spring-jack and plug are for a portable telephone set 5 for a runner or attendant who 110 can plug into the different circuits whenever desired.

By the system as above set forth it will be seen that a burglar-alarm can be manually given at any point equipped with the apparatus shown at *A* by a policeman or other party and that when this alarm is given by depression of the key *c* the phonograph *a* will be set in operation, thereupon causing a message to be transmitted over the line to the central station *C* and repeated there through the receiver *q*, and at the same time a signal is continuously given at that station to call the attention of an attendant to the message. It will also be seen that by an apparatus such as that shown at *B* the breakage or opening of the local circuit *k* by the opening of a window or door or otherwise, as desired, will automatically release the phonograph *a* and thereupon cause a message to be transmitted 125 130

to the central station and attention repeatedly called to this message. It will also be seen that whenever desired an attendant at the central station can communicate with one of the 5 alarm-stations, and also that an attendant can plug into any alarm-circuit to learn the conditions thereupon or communicate therewith, as desired.

In place of the central-station arrangement 10 herein shown the alarm apparatus can be connected with one of the circuits of a telephone-exchange operating on the common battery system. In such case the repeating signal would attract the operator's attention if she 15 were connected with the line.

It will be seen that the system herein shown can be used for other purposes than a burglar-alarm system. For example, it can be used as a fire-alarm system. In such case the 20 phonographs would be arranged to deliver messages indicating the presence and location of a fire. The apparatus could be set in operation manually, as shown at A, and automatically by arranging a local circuit *k* to 25 become broken or otherwise affected by the presence of heat—as, for example, by including in it some device normally closed—but operable to open upon the presence of an undue amount of heat, as a thermal cut-out or 30 thermostat.

It will be understood that I do not wish to limit myself to the precise apparatus herein set forth, as the same may be changed, modified, or altered without departing from the 35 spirit of my invention.

What I claim is—

1. The combination with a transmitting-circuit, a transmitter included therein, a phonograph adapted to speak into the transmitter, means for automatically causing the actuation of the phonograph, and means for automatically opening and closing the transmitting-circuit while the phonograph is operating, substantially as described.

45 2. The combination of a telephone transmitting-circuit, telephone apparatus at the central station, and an alarm apparatus at the subscriber's station, comprising means for sending a message over the telephone-circuit,

and means for opening and closing said transmitting-circuit when the message is being sent, substantially as described. 50

3. The combination of a telephone transmitting-circuit, telephone apparatus at the central station, an alarm apparatus at the subscriber's station, comprising means for sending a message over the telephone-circuit, means for producing a signal at the central station at a time when the message is being sent, and a switch operated by the reproducer 60 of the phonograph when such reproducer reaches the end of its travel, substantially as described.

4. The combination with a telephone-circuit and telephone apparatus at the central exchange and subscriber's station, of a phonograph at the subscriber's station, a transmitter connected in shunt with the telephone-circuit and arranged to receive the message of the phonograph, a switch for opening the 65 transmitting-circuit, means for operating said switch intermittently during a portion of the operation of the phonograph, and means for opening the same at the termination of the phonograph action, substantially as described. 70 75

5. The combination with a telephone-circuit, of telephone apparatus at the central exchange and also at the subscriber's station, a phonograph also at the subscriber's station, a transmitter connected in shunt with the transmitting-circuit and arranged to receive a message from the phonograph, means for opening and closing the transmitting-circuit at a time during the operation of the phonograph, means for opening the same at the termination of such operation, and a switch 80 adapted to hold the phonograph normally against operation and arranged to maintain the circuit normally open but to close the same when operated, substantially as described. 85 90

In witness whereof I hereunto subscribe my name this 19th day of November, A. D. 1902.

HAROLD D. STROUD.
